UNITED STATES PATENT OFFICE

FRANK DEBSKI, OF BROOKLYN, NEW YORK

DESIGN FOR A CHAISE LOUNGE

Application filed November 23, 1932. Serial No. 46,130. Term of patent 3½ years.

To all whom it may concern:

Be it known that I, FRANK DEBSKI, a citizen of the United States, residing in Brooklyn, in the county of Kings, and State of New York, have invented a new, original, and ornamental Design for a Chaise Lounge, of which the following is a specification, reference being had to the accompanying drawing, forming part thereof.

I claim:

The ornamental design for a chaise lounge, as shown.

FRANK DEBSKI.
